UNITED STATES PATENT OFFICE.

HARRY R. GOTTLB, OF MAPLEWOOD, MISSOURI.

DESIGN FOR AN ADVERTISING BILLBOARD.

Application filed March 21, 1927. Serial No. 21,240. Term of patent 7 years.

To all whom it may concern:

Be it known that I, HARRY R. GOTTLB, a citizen of the United States, residing at 2274 Yale Ave., Maplewood, St. Louis County, State of Missouri, have invented a new, original, and ornamental Design for Advertising Billboards, of which the following is a specification, reference being had to the accompanying drawing, forming part thereof.

Fig. 1 is a top plan view of my advertising billboard.

Fig. 2 is a perspective view of my billboard.

I claim the ornamental design for an advertising billboard, as shown.

HARRY R. GOTTLB.
